(57) **CLAIM**

The ornamental design for a shipping container handling cradle, as shown and described.

DESCRIPTION

FIG. 1 is a plan view of the shipping container handling cradle showing my new design;

FIG. 2 is a side view of the cradle;

FIG. 3 is a perspective view of the cradle;

FIG. 4 is a side view of the cradle holding a container in a raised position over a truck trailer;

FIG. 5 is an end view of the cradle on the ground supporting a container; and,

FIG. 6 is an end view showing the container being supported in a raised position by the cradle.

The broken line showing of a truck and container in the respective figures is for illustrative purposes only and forms no part of the claimed design.
